UNITED STATES PATENT OFFICE.

FRANK ZELENY AND ALBERT H. OSTBERG, OF AURORA, ILLINOIS.

HOPPER-SEAT FOR PASSENGER-CARS.

1.63.15.43.37

Specification of Letters Patent.

Patented Dec. 3, 1912.

Application filed February 12, 1912. Serial No. 677,080.

To all whom it may concern:

Be it known that we, FRANK ZELENY and ALBERT H. OSTBERG, citizens of the United States, residing at Aurora, in the county 5 of Kane and State of Illinois, have invented certain new and useful Improvements in Hopper-Seats for Passenger-Cars, of which the following is a specification.

Our invention relates in general to toilet 10 closets, and more particularly to hopper seats for passenger cars.

Our invention has for its object to provide a toilet closet or hopper with a seat which will automatically swing into a substantially vertical position when its lid is lifted, but which will be held in a horizontal closed 15 position by the weight of the lid.

A further object of our invention is to provide a toilet closet or hopper seat with 20 a spring hinge, the tension of the spring being so related to the weight of the seat and lid that when the lid is lifted into a vertical position the spring will swing the seat to and retain it in a vertical position, 25 but when the lid and seat are swung downwardly to closed positions they will remain closed, owing to the tension of the spring being insufficient to overcome their combined weight.

Our invention will be more fully described 30 in connection with the accompanying drawings in which the same is shown as embodied in a convenient and practical form, and in which—

Figure 1 is a side elevational view. Fig. 35 2 is a plan view. Fig. 3 is an enlarged horizontal sectional view through the hinge; Fig. 4 is a detail sectional view taken on the line 4—4 of Fig. 3; and Fig. 5 is a 40 detail sectional view taken on the line 5—5 of Fig. 3.

The same reference characters are used 45 to designate the same parts in the several figures of the drawings.

Reference letter A designates a closet bowl 50 or hopper, such as are used on many passenger cars.

C is a seat and D a lid, the seat and lid being hinged to a flange B around the top 55 of the hopper.

E and F designate eyes secured to the flange B in any suitable manner, as by means of screw-threaded shanks e and f projecting through the flange B and engaged 55 by clamping nuts, such as F'.

A plate G is secured to the rear under

surface of the seat C and is provided with eyes G' and G² projecting into horizontal alinement with the eyes E and F.

H' and H² designate eyes projecting from 60 the rear edge of the lid D and secured thereto by suitable fastening means. The eyes H' and H² lie outside of and aline with the eyes G' and G². A rod K extends through alined holes in the pairs of eyes E and F, 65 G' and G², and H' and H², thereby pivotally connecting the seat C and lid D with the flange B of the hopper A. Caps k' and k² engage the screw-threaded ends of the rod 70 K which project through the eyes H' and H².

A coiled spring L surrounds the rod K and is interposed between disks M' and M², located around the rod K adjacent the eyes E and F, respectively. One end l' of the 75 spring L is bent inwardly and engages a notch m' in the disk M', while the other end l² of the spring is also bent inwardly and engages a notch m² formed in the portion of the disk M² which projects within 80 the adjacent end of the spring. The spring is therefore non-rotatably connected at one end to the disk M' and at its other end to the disk M². A reduced portion O of the disk M² is non-rotatably secured within the 85 eye F by a dowel pin o.

The disk M' is provided with a series of substantially radial recesses n, into any one of which a pin N is inserted, which projects beneath the adjacent edge of the seat C, 90 preferably engaging within a notch g formed in the plate G. The tension of the spring may be adjusted by locating the pin N in different ones of the recesses n, so as to exert a sufficient lifting action upon the 95 seat C to raise the same when the lid is lifted, but insufficient to raise the seat and lid when the lid is closed.

M designates a cylindrical casing inclosing the spring and supported at its ends 100 upon annular seats formed in the inner surfaces of the disks M' and M², thereby serving to space said disks apart.

From the foregoing description it will be observed that we have invented an improvement in toilet closets or hoppers by means of which the seat will be automatically lifted to a substantially vertical position when the lid is raised, but will remain down when the lid is closed.

While we have described more or less precisely the details of construction, we do not

desire to be understood as limiting our invention thereto, as we contemplate changes in form and in the proportion of parts, and the substitution of equivalents as circumstances may suggest or render expedient without departing from the spirit of our invention.

What we claim as our invention is:

1. The combination with a toilet closet or hopper of a seat, a pair of eyes secured to said seat, a pair of eyes secured to said hopper, a rod extending through alined holes in said pairs of eyes, a coiled spring surrounding said rod between the eyes in said pairs, means locking one end of said spring to one of the eyes on the hopper, and means secured to the other end of said spring engaging said seat.
2. The combination with a toilet closet or hopper, of a seat, a pair of spaced eyes secured to said seat adjacent one edge thereof, a pair of spaced eyes secured to said hopper, a rod extending through alined holes in said pairs of eyes, a disk surrounding said rod and non-rotatably secured to one of the hopper eyes, a second disk surrounding said rod, a pin projecting from said second disk and engaging said seat, and a coiled spring surrounding said rod and secured at its ends to said disks.
3. The combination with a toilet closet or hopper, of a seat, a pair of spaced eyes secured to said seat adjacent one edge there-

of, a pair of spaced eyes secured to said hopper, a rod extending through alined holes in said pairs of eyes, a disk surrounding said rod and non-rotatably secured to one of the hopper eyes, a second disk surrounding said rod and having a series of substantially radial recesses therein, a pin removably engaging one of said recesses and engaging the adjacent edge of said seat, a coiled spring surrounding said rod and secured at its ends to said disks, and a tube inclosing said spring and supported at its ends upon said disks.

4. The combination with a toilet closet or hopper, of a seat, a pair of spaced eyes secured to said seat adjacent one edge thereof, a pair of spaced eyes secured to said hopper, means for pivotally connecting the eyes on the seat with the eyes on the hopper, a disk non-rotatably secured to one of the hopper eyes, a second disk adjacent the other of said hopper eyes, a pin projecting from said second disk and engaging said seat, and a coiled spring interposed between and secured to said disks.

In testimony whereof, we have subscribed our names.

FRANK ZELENY.

ALBERT H. OSTBERG.
